UNITED STATES PATENT OFFICE

ALPHEUS O. HURXTHAL, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

CHEMICAL LOOP DRIER CONVEYER

Application filed May 3, 1930. Serial No. 449,616.

This invention relates to a conveyer, for plastic materials, of the same general character as shown and described in my prior United States Letters Patent No. 1,772,423, 5 dated August 5, 1930.

The present invention relates to a conveyer especially adapted for use with those plastic materials which, as they are passed through a drying or other processing apparatus, have a 10 tendency to shrink in volume.

The principal object of the present invention is to construct the walls of the material-carrying openings of the conveyer in a manner to prevent the shrunken material from 15 falling therefrom.

Another object of the invention is to increase the mechanical strength and the capacity of this type of conveyer, by increasing the thickness of the conveyer.

20 This type of conveyer is adapted for general conveying purposes with plastic materials, and particularly for use in conveying plastic material through a drying apparatus, of the general type disclosed in my prior 25 United States Letters Patent No. 1,777,972, dated October 7, 1930.

I have found that when the thickness of the conveyer is increased the tendency of the plastic material to be forced out of the conveyer, as the loaded conveyer is being formed into loops in the drier, increases proportionately. This condition I have minimized by the peculiar construction of the conveyer forming the subject of the present invention, 30 and which will be fully disclosed hereinafter, reference being had to the accompanying drawings, of which:

Fig. 1 is a plan view of a conveyer made 40 in accordance with the principles of my invention;

Fig. 2 is a longitudinal section taken on the line 2—2, Fig. 1;

Fig. 3 is a transverse section taken on the 45 line 3—3, Fig. 1;

Fig. 4 is a sectional view similar to Fig. 3, but showing the conveyer as being loaded with material in a plastic state;

Fig. 5 is a sectional view similar to Fig. 4, 50 but showing the material in a shrunken state;

Fig. 6 is a plan view of a modified form of the invention;

Fig. 7 is a longitudinal section taken on the line 7—7, Fig. 6;

Fig. 8 is a plan view of another modification of the invention; 55

Fig. 9 is a longitudinal sectional elevation taken on the line 9—9, Fig. 8;

Fig. 10 is a longitudinal sectional elevation of the conveyer shown in Figs. 1 and 2 60 as it passes around an extruding roll;

Figs. 11 to 15 inclusive illustrate various modifications of wall construction for the apron units.

The conveyer shown in Figs. 1 to 5 comprises a plurality of U-shaped link elements or units 1. Each of the conveyer elements 1 comprises a pair of substantially parallel longitudinal side members 2, 2 connected at one end only by a transverse end member 3. 70

The inner face of each of the side members 2 is concaved as indicated at 4, while the outer face of each of said members is convexed as indicated at 5, see Fig. 3.

The inner face of the end member 3 is likewise concaved as indicated at 6 and the outer face of this member is convexed as shown at 7, see Fig. 2.

Adjacent the concavo-convex end member 3 of each link element 1 the concavo-convex 80 side members 2 are provided with pintle openings 9, while the free end 10 of each of said side members 2 is provided with a pintle opening 11.

The link elements 1 are assembled, to form 85 the conveyer belt, in longitudinally extending rows, in end to end relation to each other, the open end of one U-shaped element lying adjacent to but spaced from the closed end of the next preceding U-shaped element, and 90 the closed ends of the U-shaped elements of alternate longitudinal rows lying adjacent to the open ends of the U-shaped elements of the adjacent rows, in a direction extending transversely of the assembled conveyer belt. 95

Thus the conveyer belt is composed of a plurality of individual units disposed in a plurality of longitudinally extending rows and a plurality of transversely extending rows, in either of which the individual units 100

alternate with intermediate spaces, the material-carrying space 15 within each unit having concaved walls to hold the material therein, and the said intermediate spaces 16 having convexed walls for the same purpose, as clearly shown in Figs. 3, 4 and 5.

The individual units 1 are pivotally connected together by transversely extending pintles 14 which pass through the pintle openings 11 in the free ends of one unit and through the openings 9 at the closed end of the next transversely adjacent unit, across the entire width of the conveyer, the outer sides of the intermediate spaces 16 of the outer longitudinal rows being closed by closure plates 20, 20, as shown in Fig. 1.

Upon referring to the drawings, especially Fig. 3, it will be noted that the convexed surfaces of adjoining links are in abutting relation to each other along the pivot line between the transversely extending interconnected rows of units which reduces the frictional bearing surfaces between the rows to a minimum and provides for self-clearing of the conveyer at these particular points as will be more fully described hereinafter.

After the conveyer belt has been loaded with the plastic material to be treated, for the purpose of illustration I will define this treatment as a drying process which converts the material from a plastic to a more or less brittle state, the conveyer belt may be flexed in a longitudinal direction to form the apron into loops, for example, as set forth in the last mentioned co-pending application.

During this flexing of the conveyer the concavo-convex ends 3 of the individual units are to some extent free to slide in an arc through the material packed around these end members, which minimizes the tendency of the relative movement between the units to extrude the material from the spaces at either side of the end members.

In the thicker type of conveyer as disclosed herein, if the end walls 3 were straight, as in the first mentioned co-pending application, there would be a decided tendency of these straight end walls to extrude the adjacent material from the openings of the conveyer. In the thinner type of conveyer such tendency is practically negligible and, therefore, is of no consequence.

After the material has been reduced to its more or less brittle state relative movement between the transverse rows of units causes these very end walls 3 to extrude the material from the openings, the reason being that the radius of the curvature of the end walls is greater than the radius about which the wall moves as the conveyer is being flexed. For example, such flexing of the apron may be effected by being drawn out of the loops in which the conveyer hung during the processing operations.

As shown in Fig. 5, the material may

shrink, during the processing, to such an extent that the portions or pieces of the material carried in the various openings will become loosened from the walls, but due to the curvature of the wall of the opening and the corresponding curvature of wall of the piece of shrunken material within the opening the said piece of material will be held or locked within the opening, by the walls of the material impinging upon the adjacent walls of the opening in which the piece of material is disposed.

The relative circular movement between the abutting convexed walls of the conveyer units, at the pivot points, clears the conveyer at these points of any material adhering to the walls of the units at the pivot points, thus preventing any corrosion of the units at these points as would be caused by a chemical action set up by some kinds of plastic material if the same were permitted to remain on the conveyer.

In order to remove the material from the openings, which does not fall therefrom when relative flexing of the units is effected, I pass the conveyer over a toothed extruding roll 25, see Fig. 10, the teeth 26 thereof entering the material-carrying cavities 15 and 16 of the conveyer and forcing the material out of these openings in the manner substantially as shown in said figure.

In Figs. 6 and 7, I have shown a modification of the invention in which each of the units 1a comprises a complete rectangular element consisting of oppositely disposed sides 2a, 2a, and oppositely disposed end walls 3a, 3a, which when assembled by pintles 14a form a complete conveyer having material-receiving openings 15a and 16a. The action of this type of conveyer is substantially the same as the conveyer shown in Figs. 1 to 5.

In the modification shown in Figs. 8 and 9, the conveyer is constructed in the same manner as in Figs. 1 to 5 with the addition of supplementing transversely extending bars 14b which pass through the material-carrying cavities 15b, 16b, to assist in holding the shrunken material therein. The extruding action by the toothed roll 25 is clearly shown in Fig. 10.

Obviously, the side walls of the material-receiving openings may be of any of the cross-sectional forms shown in Figs. 11 to 14 inclusive.

From the above, it will be obvious that by producing a conveyer apron having material-carrying openings of which the walls are disposed on either converging or diverging angles relative to each other and relative to the plane of the conveyer the material when shrunken will be retained within the cavities until extruded therefrom by a relative flexing action between the units or by

an extruding device, such as shown in Fig. 10, or both.

The apron may also be subjected to a beating action, if desired, to replace the above methods of removal of the material, or the beating action may be used as a supplement to such methods if desired.

I claim:

1. A conveyer for plastic materials having substantially parallel faces and a plurality of material-receiving openings extending through the conveyer from one to the other of said faces thereof, the area of each opening varying at different planes intermediate the said faces of the conveyer.

2. A conveyer for plastic materials having substantially parallel faces and a plurality of material-receiving openings extending through the conveyer from one to the other of said faces thereof, the area of each opening varying at different planes intermediate the said faces of the conveyer and the smaller areas of at least some of said openings being disposed adjacent the said faces of the conveyer, while the larger areas of such openings are disposed intermediate said faces.

3. A conveyer for plastic materials having substantially parallel faces and a plurality of material-receiving openings extending through the conveyer from one to the other of said faces thereof, the area of each opening varying at different planes intermediate the said faces of the conveyer and the larger areas of at least some of said openings being disposed adjacent the said faces of the conveyer, while the smaller areas of such openings are disposed intermediate said faces.

4. A conveyer for plastic materials having substantially parallel faces and a plurality of material-receiving openings extending through the conveyer from one to the other of said faces thereof, the area of each opening varying at different planes intermediate the said faces of the conveyer the smaller areas of some of said openings being disposed adjacent the said faces of the conveyer with the larger areas of such openings disposed intermediate said faces, and the remaining openings having their larger areas adjacent the said faces and their smaller areas intermediate said faces.

5. A conveyer for plastic materials having substantially parallel faces and a plurality of material-receiving openings extending through the conveyer from one to the other of said faces thereof, the area of each opening varying at different planes intermediate the said faces of the conveyer the smaller areas of some of said openings being disposed adjacent the said faces of the conveyer with the larger areas of such openings disposed intermediate said faces, and the remaining openings having their larger areas adjacent

the said faces and their smaller areas intermediate said faces the openings included in the first said group alternating with the openings included in the second said group.

6. A conveyer for plastic materials having substantially parallel faces and a plurality of material-receiving openings extending through the conveyer from one to the other of said faces thereof, the area of each opening varying at different planes intermediate the said faces of the conveyer the smaller areas of some of said openings being disposed adjacent the said faces of the conveyer with the larger areas of such openings disposed intermediate said faces, and the remaining openings having their larger areas adjacent the said faces and their smaller areas intermediate said faces the openings included in the first said group alternating in a direction longitudinally of the conveyer with the openings included in the second said group.

7. A conveyer for plastic materials having substantially parallel faces and a plurality of material-receiving openings extending through the conveyer from one to the other of said faces thereof, the area of each opening varying at different planes intermediate the said faces of the conveyer the smaller areas of some of said openings being disposed adjacent the said faces of the conveyer with the larger areas of such openings disposed intermediate said faces, and the remaining openings having their larger areas adjacent the said faces and their smaller areas intermediate said faces the openings included in the first said group alternating in a direction transversely of the conveyer with the openings included in the second said group.

8. A conveyer for plastic materials having substantially parallel faces and a plurality of material-receiving openings extending through the conveyer from one to the other of said faces thereof, the area of each opening varying at different planes intermediate the said faces of the conveyer the smaller areas of some of said openings being disposed adjacent the said faces of the conveyer with the larger areas of such openings disposed intermediate said faces, and the remaining openings having their larger areas adjacent the said faces and their smaller areas intermediate said faces the openings included in the first said group alternating with the openings included in the second said group in directions longitudinally and transversely of the conveyer.

9. A conveyer for plastic materials having substantially parallel faces and a plurality of material-receiving openings extending through the conveyer from one to the other of said faces thereof, the area of each opening varying at different planes intermediate the said faces of the conveyer, and means for extruding the material from said openings.

10. A conveyer for plastic materials having substantially parallel faces and a plurality of material-receiving openings extending through the conveyer from one to the other of said faces thereof, the area of each opening varying at different planes intermediate the said faces of the conveyer, and means for extruding the material from said openings comprising an element having projections adapted to enter said openings.

11. A conveyer for plastic materials having substantially parallel faces and a plurality of material-receiving openings extending through the conveyer from one to the other of said faces thereof, the area of each opening varying at different planes intermediate the said faces of the conveyer, means for extruding the material from said openings comprising a roll around which said conveyer is adapted to pass, and projections on said roll adapted to enter said openings.

12. A conveyer for plastic materials having substantially parallel faces and a plurality of material-receiving openings extending through the conveyer from one to the other of said faces thereof, the area of each opening varying at different planes intermediate the said faces of the conveyer, and rods extending through said openings to assist in retaining the material therein.

13. A conveyer for plastic materials having substantially parallel faces and a plurality of material-receiving openings extending through the conveyer from one to the other of said faces thereof, the area of each opening varying at different planes intermediate the said faces of the conveyer, rods extending through said openings to assist in retaining the material therein, and means for extruding the material from said openings comprising an element having projections adapted to extend into said openings between the said rods and the walls of the openings.

14. A conveyer for plastic materials comprising a plurality of pivotally connected link elements having concavo-convex end walls extending transversely of the conveyer.

15. A conveyer for plastic materials comprising a plurality of pivotally connected link elements having concavo-convex end walls extending transversely of the conveyer, the axes of the curvatures of said end walls being spaced apart from the connecting pivots longitudinally of the conveyer.

16. A conveyer for plastic materials comprising a plurality of pivotally connected link elements having concavo-convex end walls extending transversely of the conveyer, the axes of the curvatures of said end walls being spaced apart from the connecting pivots longitudinally of the conveyer and the cords of the segmental arcs forming said end walls being disposed in planes substantially perpendicular to the general plane of the conveyer.

17. A conveyer for plastic materials comprising a plurality of pivotally connected link elements having concavo-convex side members extending longitudinally of the conveyer with the convex surfaces of adjacent link elements abutting at the connecting pivots.

18. A conveyer for plastic materials comprising a plurality of pivotally connected link elements having concavo-convex side members extending longitudinally of the conveyer with the convex surfaces of adjacent link elements abutting at the connecting pivots and transversely extending end members connecting the said side members of the link elements respectively.

19. A conveyer for plastic materials comprising a plurality of pivotally connected link elements having concavo-convex side members extending longitudinally of the conveyer with the convex surfaces of adjacent link elements abutting at the connecting pivots and transversely extending concavo-convex end members connecting the said side members of the link elements respectively.

20. A conveyer for plastic materials comprising a plurality of pivotally connected substantially U-shaped link elements each comprising a pair of substantially parallel concavo-convex side members and a concavo-convex end member connecting said side members at one end thereof.

21. A conveyer for plastic materials comprising a plurality of pivotally connected substantially U-shaped link elements each comprising a pair of substantially parallel concavo-convex side members and a concavo-convex end member connecting said side members at one end thereof, the said link elements being assembled in parallel longitudinal rows, the open ends of the link elements of one row lying adjacent the closed ends of the link elements of adjacent rows transversely of the conveyer.

22. A conveyer for plastic materials comprising a plurality of pivotally connected substantially U-shaped link elements each comprising a pair of substantially parallel concavo-convex side members and a concavo-convex end member connecting said side members at one end thereof, the said link elements being assembled in parallel longitudinal rows, the open ends of the link elements of one row lying adjacent the closed ends of the link elements of adjacent rows transversely of the conveyer, and pintles extending transversely of the conveyer through the adjacently positioned ends of the link elements of all of said longitudinally extending rows thereof.

23. A conveyer for plastic materials comprising a plurality of pivotally connected substantially U-shaped link elements each comprising a pair of substantially parallel concavo-convex side members and a concavo-

convex end member connecting said side members at one end thereof, the said link elements being assembled in parallel longitudinal rows, the open ends of the link elements 5 of one row lying adjacent the closed ends of the link elements of adjacent rows transversely of the conveyer, and pintless extending transversely of the conveyer through the adjacently positioned ends of the link elements 10 of all of said longitudinally extending rows thereof, the convex surfaces of the said adjacently positioned link elements abutting at the pivots.

24. A conveyer for plastic materials comprising a plurality of pivotally connected substantially U-shaped link elements each comprising a pair of substantially parallel concavo-convex side members and a concavo-convex end member connecting said side 20 members at one end thereof, the said link elements being assembled in parallel longitudinal rows, the open ends of the link elements of one row lying adjacent the closed ends of the link elements of adjacent rows 25 transversely of the conveyer, pintles extending transversely of the conveyer through the adjacently positioned ends of the link elements of all of said longitudinally extending rows thereof, and rods extending transversely 30 of the conveyer intermediate the longitudinally spaced pintles.
